UNITED STATES PATENT OFFICE.

PAUL H. SCHMIDT, OF MILWAUKEE, WISCONSIN, ASSIGNOR TO NOVELTY KNITTING MILLS, OF MILWAUKEE, WISCONSIN.

DESIGN FOR A KNITTED CAP.

49,972.

Specification for Design.

Patented Nov. 28, 1916.

Application filed October 9, 1916. Serial No. 124,743. Term of patent 3½ years.

To all whom it may concern:

Be it known that I, PAUL H. SCHMIDT, a citizen of the United States, residing at Milwaukee, in the county of Milwaukee and State of Wisconsin, have invented a new, original, and ornamental Design for Knitted Caps, of which the following is a specification, reference being had to the accompanying drawing, forming part thereof.

The figure is an elevation of a knitted cap, showing my new design.

Copies of this patent may be obtained for five cents each, by addressing the "Commissioner of Patents, Washington, D. C."

I claim:

The ornamental design for a knitted cap, as shown.

In testimony that I claim the foregoing I have hereunto set my hand at Milwaukee, in the county of Milwaukee and State of Wisconsin, in the presence of two witnesses.

PAUL H. SCHMIDT.
